[57] CLAIM

The ornamental design for a telecommunication receiver, as shown and described.

DESCRIPTION

FIG. 1 is a top plan view of a telecommunications receiver showing my new design;

FIG. 2 is a rear elevational view;

FIG. 3 is a left side elevational view;

FIG. 4 is a front elevational view;

FIG. 5 is a right side elevational view;

FIG. 6 is a bottom plan view;

FIG. 7 is a perspective view thereof in an alternate condition in which the display is not visible; and,

FIG. 8 is a perspective view thereof, the display being visible with the characters displayed therein being shown by means of broken lines for illustrative purposes only and forming no part of the claimed design.
